Primary Examiner — Lilyana Bekic*Assistant Examiner* — Lee D. Starr(74) *Attorney, Agent, or Firm* — Shackelford, Bowen, McKinley & Norton, LLP(57) **CLAIM**

The ornamental design for an eczema relief product, as shown and described.

DESCRIPTION

FIG. 1 is a top perspective view of an eczema relief product in accordance with the design;

FIG. 2 is a top view thereof;

FIG. 3 is a right side perspective view thereof;

FIG. 4 is a left side bottom perspective view thereof; and

FIG. 5 is a bottom perspective view thereof; and,

FIG. 6 is a left side perspective view thereof.

The broken lines in the drawings depict portions of the eczema relief product that form no part of the claimed design.

1 Claim, 6 Drawing Sheets(56)
